PICTURE TAKING HOUSING FOR CHECK IDENTIFICATION

Gustave Fassin, Los Gatos, Calif., assignor to R. H. Peterson, San Jose, Calif., and Harry Buller, Bakersfield, Calif.

Application August 8, 1955, Serial No. 37,352

Term of patent 3½ years

(Cl. D61—1)

FIG-1

FIG-2

FIG-3

FIG-4

Fig. 1 is a perspective view of a picture taking housing for check identification showing my new design.

Fig. 2 is a front view of the housing shown in Fig. 1.

Fig. 3 is a side elevational view of the housing of Fig. 1.

Fig. 4 is a top plan view of the housing of Fig. 1.

I claim:

The ornamental design for a picture taking housing for check identification, as shown.
